Atty.

UNITED STATES PATENT OFFICE.

JAMES IRWIN BARNHURST, OF PHILADELPHIA, PENNSYLVANIA.

UMBRELLA.

SPECIFICATION forming part of Letters Patent No. 349,476, dated September 21, 1886.

Application filed May 5, 1886. Serial No. 201,137. (No model.)

To all whom it may concern:

Be it known that I, JAMES IRWIN BARNHURST, a citizen of the United States, residing at the city and county of Philadelphia, and State of Pennsylvania, have invented certain new and useful Improvements in Umbrellas, of which the following is a full, clear, and exact description, reference being had to the accompanying drawings, of which—
10 Figure 1 represents a detached rib and stretcher of an umbrella having my invention applied thereto. Fig. 2 is a section, as on line *a b*, Fig. 1. Fig. 3 is a similar sectional view of the invention, in connection with a solid stretcher, instead of the fluted or "Paragon" frame stretcher. Fig. 4 is a medial longitudinal section of an umbrella-frame in which the invention is embodied with the ribs sprung out. Fig. 5 is a like sectional view with the 20 ribs closed or folded.

The object of this invention is to provide an improved means for causing the ribs of umbrella-frames to be thrown outwardly from the stick, whereby the free ends of the ribs, 25 when released from the closed position, are retained at a considerable distance from the stick, and thus the hand is permitted to readily operate the runner in order to open the umbrella, and, secondly, whereby the locking 30 of the ribs, frequently occurring with ordinary umbrellas, is obviated.

Referring now to the annexed drawings, *a* are the ribs, *b* the stretchers, *c* the stick, and *d* the runner, of an ordinary umbrella or parasol. At a point adjacent to the pivotal connection *x* of the respective ribs and stretchers I secure to each of the former, in a convenient manner, a lug or spud, *E*, that projects inwardly toward the stretcher *b*, and which 35 spud, when the frame is entirely or nearly closed, impinges against the stretcher, as shown in the drawings. I prefer to form and attach the said lug to the frame in the following manner: I take a piece of sheet-iron or other metal, and by means of well-known tools, bend 40

and close the same firmly around the rib, so that it will be retained securely in place. These lugs may be readily applied to ordinary umbrellas, and they may be set at any desired distance from the connection of the ribs and 50 stretchers.

The normal relative position of the stretchers when the projections *E* are in contact therewith is seen in Figs. 1 and 4, and this position they instantly assume, owing to the elasticity 55 of the ribs, when the ends of the latter are released from the usual sliding cup, *f*, or other holding device. When they occupy this position, the hand can freely reach the runner, and the umbrella may be opened without any 60 locking or interference of the parts, for the reason that the ribs are prevented from coming upon or passing inwardly beyond the center of their pivotal connections *x*.

Lugs *E* may be secured to the stretchers in 65 lieu of the ribs with the same results.

I am aware of the fact that the stretchers of umbrellas and parasols have been provided near their pivotal connections with the ribs with an outward bend or angle constituting a 70 shoulder, against which the ribs impinged, thus tending to spring the latter out from the stick when the ends of the ribs were released from the retaining-cup when the umbrella is closed. I do not, therefore, claim that construction to 75 be comprised by my present invention.

Having thus described my invention, I claim as new and desire to secure by Letters Patent—

In an umbrella-frame, the combination, with the ribs and stretchers, of the lugs *E*, made 80 separate from the frame and secured thereto, and adapted to operate substantially as and for the purpose specified.

In testimony whereof I have hereunto affixed my signature this 9th day of April, A. 85 D. 1886.

JAMES IRWIN BARNHURST.
